(57) **CLAIM**

The ornamental design for wireless charging power base dual, as shown and described.

DESCRIPTION

FIG. 1 is front top right perspective view of a wireless charging power base dual of the invention.

FIG. 2 is a top view thereof.

FIG. 3 is a front view thereof.

FIG. 4 is a left side view thereof.

FIG. 5 is a rear view thereof.

FIG. 6 is a right side view thereof; and,

FIG. 7 is a bottom view thereof.

1 Claim, 5 Drawing Sheets

FIG. 1

FIG. 2

FIG. 3

FIG. 5

FIG. 4

FIG. 6
